(57) **CLAIM**

The ornamental design for a pet house as shown.

DESCRIPTION

FIG. 1 is a front, left, and top perspective view of a pet house, showing my new design;

FIG. 2 is a rear, right, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines and the shaded areas bounded by broken lines depict portions of the pet house that form no part of the claimed design.

1 Claim, 8 Drawing Sheets
